US00D616435S

(12) **United States Design Patent**
Kurosawa et al.

(10) **Patent No.:** **US D616,435 S**
(45) **Date of Patent:** **** May 25, 2010**

(54) **PERSONAL COMPUTER**

(75) Inventors: **Yu Kurosawa**, Kawasaki (JP); **Hisao Morooka**, Kawasaki (JP); **Hiroyuki Fujita**, Tokyo (JP)

(73) Assignee: **Fujitsu Limited**, Kawasaki (JP)

(**) Term: **14 Years**

(21) Appl. No.: **29/311,991**

(22) Filed: **Aug. 17, 2009**

(30) **Foreign Application Priority Data**

Apr. 14, 2009 (JP) 2009-008456

(51) **LOC (9) Cl.** **14-02**

(52) **U.S. Cl.** **D14/318**

(58) **Field of Classification Search** ..... D14/315-327, D14/341-345, 331, 130; D18/1, 2, 7, 11; 178/17 A, 17 C; 345/102, 104, 156, 163, 345/168; 341/22, 23; 361/679.08, 679.09, 361/679.26, 679.27; 400/486, 489
